FOREIGN PATENT DOCUMENTS

EP 611282 B1 8/1999

Primary Examiner — Karen E Eldridge Powers(74) *Attorney, Agent, or Firm* — Shook, Hardy & Bacon L.L.P.(57) **CLAIM**

The ornamental design for a toothbrush, as shown and described.

DESCRIPTION

FIG. 1 is a perspective view of the toothbrush showing my new design according to an embodiment hereof;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines are directed to environment and form no part of the claimed design.

1 Claim, 3 Drawing Sheets(56)
